DESIGN FOR A BELT FOR WEARING APPAREL

Henry Auslander, New York, N. Y.

Application November 9, 1936, Serial No. 65,794

Term of patent 7 years

To all whom it may concern:

Be it known that I, Henry Auslander, a citizen of the United States and resident of New York city, in the county of New York and State of New York, have invented a new, original, and ornamental Design for a Belt for Wearing Apparel, of which the following is a specification, reference being had to the accompanying drawing, forming part thereof.

Fig. 1 is a top plan view of a belt for wearing apparel, showing my new design.

Fig. 2 is an edge view of Fig. 1.

Fig. 3 is a bottom plan view of Fig. 1.

I claim:

The ornamental design for a belt for wearing apparel, as shown.

HENRY AUSLANDER.
